[57] CLAIM

The ornamental design for a display container, as shown and described.

DESCRIPTION

FIG. 1 is a top, right, front perspective view of a display container showing the design of the present invention; FIG. 2 is a right side view thereof, which is a mirror image of the left side thereof;

FIG. 3 is a front view thereof;

FIG. 4 is a rear view thereof;

FIG. 5 is a top view thereof;

FIG. 6 is a bottom view thereof.

FIG. 7 is a top, right, front perspective view of an alternative embodiment of a display container having a design of the present invention.

The corresponding views of the second embodiment (FIG. 7) are same as disclosed in FIGS. 2–6 of the first embodiment with the exception of the dangling flag configuration.
